UNITED STATES PATENT OFFICE.

ABRAHAM NOVICK, OF NEW YORK, N. Y., ASSIGNOR TO UNITED STATES ENVELOPE COMPANY, OF SPRINGFIELD, MASSACHUSETTS, A CORPORATION OF MAINE.

ENVELOP-MACHINE.

1,298,776.

Specification of Letters Patent.

Patented Apr. 1, 1919.

Substitute for application Serial No. 859,610, filed September 1, 1914. This application filed July 23, 1917. Serial No. 182,195.

To all whom it may concern:

Be it known that I, ABRAHAM NOVICK, a citizen of the United States, and a resident of the city of New York, county of Kings, 5 and State of New York, have invented certain new and useful Improvements in Envelop-Machines, of which the following, together with the accompanying drawings, is a specification.

10 The present invention relates to envelop machines, this application being a continuation of my copending application Serial No. 859,610, filed September 1, 1914.

15 My invention, as hereinafter described, resides in the provision of novel instrumentalities for making completed envelopes from previously cut blanks or sheets at a high rate of speed and with extreme uniformity and perfection in the resulting product. The invention, as fully pointed out hereinafter, resides more particularly in the novel instrumentalities for facilitating and completing the several folding operations on the blanks which are requisite in the manufacture of 20 envelopes, and in a construction of such instrumentalities which renders them readily adjustable to the manufacture of envelopes of various sizes and shapes, from blanks of widely different conformation. The invention 25 is fully set forth in the following description and pointed out in the annexed claims, reference being had in this connection to the accompanying drawings, in which—

30 Figure 1 is a side view of so much of an envelop machine as is necessary for the illustration of my present improvements.

35 Fig. 2 is a top plan view of the mechanism which is shown in Fig. 1.

40 Fig. 3 is a longitudinal sectional view of the mechanism, on the line 3—3 of Fig. 2.

45 Fig. 4 is a fragmentary transverse view of the mechanism, partly in section, and showing the side or end flap folding mechanism.

50 Fig. 5 is a fragmentary sectional view on the line 5—5, Fig. 4.

Fig. 6 is a detached view illustrating the operation of the back flap folding mechanism.

55 Fig. 7 is a similar view to Fig. 6, showing the parts in a different position.

Fig. 8 is a view at right angles to Figs. 6 and 7, of the parts therein shown.

Fig. 9 is a detached view of the seal flap 55 folding mechanism.

Figs. 10 and 11 are views illustrating two of the different styles of envelopes, and shapes of blanks, to which my machine is readily adaptable.

Like reference characters refer to like parts in the different figures.

The mechanism constituting my invention is herein shown as supported transversely between two spaced side frames or standards 1, 1, which extend longitudinally of the machine, and which afford suitable bearings for the ends of the several shafts extending transversely therebetween. One such shaft is the main driving shaft 2 of the machine, 65 which carries a belt pulley 3, or other equivalent means, by which it is continuously rotated from any suitable source of power, not shown. Said shaft 2 carries a gear 4 which is in mesh with a gear 5 on a lower shaft 6, whereby said shafts 2 and 6 rotate in opposite directions. The shaft 6 carries an elongated roll 7 which constitutes the driving means for a plurality of endless belts or tapes 8, encircling said roll. Forwardly of the roll 7 said belts 8 encircle a roll 9 which is journaled near the end of a stationary yoke 10, carried on a transverse rod or bar 11 from the fixed framework. The upper courses of belts or tapes 8 pass 70 over and around the two rolls 7 and 9, as shown in Fig. 3, and said belts thus constitute the conveying mechanism for the envelop blanks to advance them successively 75 in the plane of their flat or extended positions. Said blanks may be fed or delivered 80 one by one to the belts or tapes 8 by any suitable mechanism commonly found in machines of this class, the details of which mechanism form no part of the present invention and hence are not herein shown.

The blanks are fed to the belts or tapes 8, and as so fed, their advancement by said tapes is facilitated by the action of roll 12 85 which is carried on shaft 2 immediately above the roll 7, with its peripheral surface in contact with said belts or tapes 8.

The belts or tapes 8 support each blank in the plane of its flat or extended position 90 with its back or bottom flap in the lead, and with its side or end flaps projecting laterally and overhanging said belts or tapes. The above is true whether the envelop to be 95

formed is made from the usual rhomboidal blank with substantially triangular flaps, or whether it be of the form shown in Figs. 10 or 11, in which a, a' respectively indicate the back or bottom flaps, b, b' respectively the side or end flaps and c, c' respectively the seal flaps. Whatever the form of blank, the illustrated embodiment of my invention contemplates the application of moist gum to the under surfaces of the projecting side or end flaps while the blank is in transit on the tapes 8, and to this end rotating gumming members 13 are mounted on a shaft 14 below the belts 8. These gumming members provide gumming segments, not shown, of the requisite shape and extent for gumming the edges of the under surfaces of the side or end flaps of the blank; obviously, a number of such members 13 may be provided for interchangeable use on the shaft 14 to take care of different sizes and shapes of blanks. A pressing roller 15 is mounted on a shaft 16 directly above the gumming members 13 to insure contact between the edges of the blank and the gumming segments, and said shafts 14 and 16 carry intermeshing gears 17 and 18 respectively, whereby their rotation in unison is effected. The gear 17 is in mesh with a gear 19 on shaft 20, which carries a gum transferring cylinder 21 for supplying gum to the gumming segments of members 13. Said cylinder 21 is supplied with gum from a gum roll 22, which is carried on a shaft 23 and rotates partially submerged in a gum box 24, of ordinary construction, containing a supply of liquid gum or adhesive. The gear 19 on shaft 20 is in mesh with an idle gear 25 on stud 26, which in turn receives its rotation from a second idle gear 27 on stud 28, the latter being in mesh with the gear 5 of shaft 6. The above described gearing serves to rotate shafts 14, 16 and 20 of the gumming mechanism in proper relation to the travel of the blanks on belts 8, whereby gum is applied to the under surfaces of their side flaps as each blank moves forward in the machine. The shaft 23 of gum roll 22 has a gear 29 which is also in mesh with gear 19, for the driving of said roll, as shown in Fig. 1. The side flap gumming mechanism as above described is merely illustrative of one way of carrying my invention into practice, since it will be clear that the same of itself forms no part of my invention; if desired, the blanks may be gummed previous to their introduction to the machine as herein shown and described, or instead of gumming the side flaps as here contemplated for adhesion to the back or bottom flap when the latter is folded, said side flaps may be folded ungummed, and the back flap may be gummed for adhesion to said side flaps.

Irrespective of the gumming operation or how it is performed, the blanks in their ad-

vance by the belts 8 are preferably held in frictional contact with said belts by a series of gravity rollers or balls 30, 30, which are retained in suitable sockets or bearings of a plate 31, depending from a transverse bar 32 from the fixed framework. By thus imposing a slight weight on each blank as it moves forward with the upper courses of belts 8, the liability for slippage or de-registration of the blank is decreased. Each blank is delivered by the belts 8 onto a table 33, whose upper surface is in substantially the same plane as the upper courses of said belts, said table being supported on arms 34 projecting from the yoke 10. The leading edge 80 of the back or bottom flap of the blank is carried beyond the edge of the table 33 until the blank is brought to rest by contact with suitable stops as hereinafter described, and in this position of rest the rearmost part 85 of the blank may overhang and rest upon the adjacent portions of belts 8. In this fashion, each blank is still under the influence of the forwarding and advancing means when brought to rest on the table 33, with the result that it is brought evenly and squarely against the stops which arrest its movement, and hence it is squared and alined in preparation for the operation of the folding devices hereinafter described.

The stops which arrest the movement of the blank on the table 33 are two in number, one on each side of the blank, and they are here designated at 35, 35, as the lower ends of rods 36, 36, which depend from the free ends of crossed members 37 and 38, Figs. 2 and 4. The member 37 is attached to a carrier 39 on the opposite side of the machine from its stop 35, and the member 38 is attached to a similar carrier 40 on the opposite side of the machine from its stop 35. The two carriers 39 and 40 are movable in opposite directions simultaneously toward and away from each other, by reason of their engagement with right and left hand screws 105 41 and 42 respectively on a common oscillating shaft 43, for a purpose hereinafter described. The stops 35 are caused to move in opposite directions simultaneously toward and away from each other, and because of 110 their connection to the crossed members 37 and 38, their movements are the reverse of the movements of carriers 39 and 40. When the stops 35 are widely separated, they are out of the way of a blank arriving on the 115 table 33, but when drawn together, they are in position to intercept and arrest the movement of such a blank by contact with portions of its advancing edge, as for instance the reentrant angles d, d' of the blank shown in Fig. 10, or the reentrant angles d', d' of the blank shown in Fig. 11. The joint action of these stops 35 is to aline and center the blank both longitudinally and laterally, as will be readily understood, but it will be 120 125 130

clear that my invention is not limited or confined to the use of stops or squaring and centering devices having this particular mode of operation, since the folding and envelop forming functions of my machine are as well served by the use of any known type of centering and squaring devices for the blank.

The shaft 43 carries an arm 44 which is pivotally connected by a link 45 with a 10 crank 46 on shaft 14. In this manner, the desired oscillation, in time with the operation of the machine, is imparted to the shaft 43, it being clear that the degree of oscillation can be regulated for various sizes 15 of blanks by an adjustable pivotal connection 47, or in any other well known manner.

The carriers 39 and 40 support horizontal forming plates 54, 54 from their lower ends, directly over the blank as it lies on 20 table 33. The outer lateral edges of these plates are utilized for the folding of the side flaps of the blank, and the front edges are utilized for the folding of the back or bottom flaps of the blank. When a blank is 25 approaching the table 33, the plates 54 are close together near the center of the machine, and the stops 35 are consequently widely separated. Substantially coincident with the arrival of the blank on table 33, 30 the plates, by the movement of carriers 39 and 40 along shaft 43, begin to separate, and at the same time the stops are drawn inwardly to effect the centering and squaring function which has already been described. At the limit of outward movement 35 to which the plates are adjusted for a blank of given size and shape, the outer lateral edges of said plates correspond to the lines of fold of the side flaps, and in this position, the mechanism is in readiness for the 40 operation of the side flap folding devices, which will now be described. It is to be understood that the forming plates 54, described above as being movable transversely 45 of the machine, could, if desired, have these motions dispensed with, the same as the stops 35, without departing from the spirit of my invention.

The side flap folding devices, for coöperation with the lateral edges of plates 54, 54 consist of movable folding plates 55, 55 on opposite sides of table 33, these plates being carried adjustably on the inner ends of arms 56. As shown in Fig. 2, the plates 55 have elongated slots 57 through which 55 pass retaining bolts 58 for securing each plate in the desired position of adjustment with respect to its corresponding arm 56. Each arm 56 has a substantially square opening 59 therein, within which opening works an approximately triangular cam 60, mounted on a rock shaft 61, as shown on both sides of the machine in Fig. 4. Each shaft 61 is journalized in a bracket 62 that is 60 secured in any suitable manner, as by bolts 65

63, 63, to the side frames 1, 1. The brackets 62 also provide journals for operating rock shafts 64, 64, the latter having gear segments 65, 65 thereon, each of which is in mesh with a gear segment 66 on a corresponding cam shaft 61. One of the rock shafts 64 is operated by an arm 67 having an adjustable pivotal connection 68 with a rod 69, which is connected to an eccentric 70 on a shaft 71. The shaft 71 is rotated 75 continuously, in timed relation to the operation of the machine, through bevel gearing 72, 72 from the shaft 23, Fig. 1. The motion of the operating rock shaft 64 is communicated in the opposite direction to the 80 other rock shaft 64 by means of a link 73, having a pivotal connection 74 with an arm 75 depending from said second rock shaft, said link being pivotally connected at its opposite end to the gear segment 65 of first 85 rock shaft 64.

The outer end of each arm 56 carries a roller 76, which is movable in a substantially horizontal guide or slot 77 provided by a bracket 78. The outer ends of arms 56 90 being thus constrained to move in a substantially horizontal path, the motion imparted to the inner ends of said arms carrying the folding plates 55 is as follows:—The partial rotation of each cam shaft 61 in one direction operates, through cam 60 and square opening 59, to first raise and then move inward horizontally the corresponding folding plate 55. The reverse oscillation of each cam moves the corresponding folding 100 plate outward horizontally and then down. The inward and outward horizontal motions thus imparted may be modified by providing a slight offset 79 in each slot 77, thus facilitating the folding operation performed by the plates 55 on the side flaps of the blank. It will be understood that at the start of the side flap folding operation, the plates 55 are disposed below the extended side flaps of the blank which overhang 110 the lateral edges of table 33. The plates 55 rise simultaneously, thus turning up said side flaps, and then said flaps move inward simultaneously toward each other, thus folding said side flaps over the lateral outer edges of forming plates 54, the latter at this time having reached the limit of their movement away from each other. The subsequent outward and downward movement of plates 55 in position to act upon the next blank arriving on table 33, is accompanied 120 by the inward movement of forming plates 54 and the outward movement of stops 35, to release the blank for the operation thereon of the back flap folding mechanism, 125 which will now be described.

A pair of disks 80 are mounted on an oscillating shaft 81, the latter having an arm 82 which is pivotally connected by a link 83 with a crank 84 on shaft 14. The rota-

tion of shaft 14 thus rocks the shaft 81 and disks 80, the throw or degree of movement of the latter being regulated by means of an adjustable pivotal connection 85, or any other well known manner. The disks 80 have eccentrically journaled therein the trunnions of a roll 86, Figs. 6, 7 and 8, to which is secured a pinion 87 that meshes with an idle gear 88, also carried eccentrically by one of the disks 80. The gear 88 is in mesh with a gear 89 carried by a hollow shaft 90, which surrounds the oscillating shaft 81 and is rotated continuously by a gear 91 in mesh with an idle gear 92 on stud 93, the latter being driven from gear 17 of shaft 14.

For coöperation with the roll 86, the disks 80 support a roll 94 which is carried by arms 95, 95, one on each disk and pivoted eccentrically thereto at 96, 96. The roll 94 is pressed against the periphery of roll 86 by means of springs 97, 97, which are attached to the arms 95, as shown in Figs. 6 and 7, and to the respective disks 80 on which said arms are pivoted. During the oscillatory movements of disks 80, the roll 86, carried thereby, is rotated continuously in a counter-clockwise direction, Figs. 3, 6 and 7, by reason of the planetary movement of pinion 87 and idle gear 88 about the driving gear 89 of said roll. While the blank on table 33 is having its side flaps folded, the rolls 86 and 94 occupy the position shown in Fig. 3, the roll 94 being below the extended bottom or back flap of the blank. After the folding of the side flaps, the disks 80 are rocked upwardly, carrying the rolls 86 and 94 into the position shown in Fig. 6, causing the roll 94 to turn up and fold the back or bottom flap of the envelop over the adjacent edges of forming plates 54. The folded edge thus formed is taken in the bight of rolls 94 and 86, and by rotation of roll 86 as above described, the partly folded blank is moved off of table 33 coincident with the downward oscillation of disks 80, as shown in Fig. 7. The passage of the partly folded envelop between rolls 86 and 94 presses the folded back or bottom flap into secure contact with the previously gummed edges of the folded side flaps, thus completing the back wall of the envelop.

As it passes from the bight of rolls 86 and 94, the partly folded envelop is delivered to the bight of forwarding rolls 98 and 99, the roll 98 being preferably segmental in form, as shown in Fig. 3, to allow for increased speed of travel of the envelop. The rolls 98 and 99 are carried on shafts 100 and 101 respectively, which have intermeshing gears 102, 103, the latter being driven from a gear 104 on a shaft 105, which in turn is rotated continuously by bevel gearing 106 from shaft 71. From the bight of forwarding rolls 98 and 99, the partly

folded envelop passes over a roll 107 on shaft 108, the latter having a gear 109 in mesh with gear 104 of shaft 105. The roll 107 coöperates with a gumming segment 110 to gum the free edge of the extended seal flap of the blank as said seal flap passes therebetween. This gumming segment 110 is mounted between disks 111, 111 on a shaft 112, which has a gear 113 in mesh with the gear 109 of shaft 108. The segment 110 receives its gum from a transfer roll 114 on shaft 115, the latter being driven by a gear 116 in mesh with gear 113, and also in mesh with the gear 117 on the shaft 118 of a gum roller 119. The latter rotates in a gum box 120 of usual construction and assists in the usual manner in supplying gum to the segment 110.

The disks 111 coöperate with the roll 107 in forwarding the partly folded envelop from the seal flap gumming mechanism to the bight of forwarding disks 121, 121 and a roll 122, it being understood that the above described specific seal flap gumming mechanism of itself forms no part of my invention, since any well known type of such mechanism could be employed. The disks 121, 121 and roll 122 are mounted on shafts 123, 123 which carry intermeshing gears 124, 124, one of which is in mesh with a gear 125 on a shaft 126. The latter gear 125 is also in mesh with gear 109 on shaft 108, so as to continuously drive the disks 121 and roll 122. It will be understood that the disks 121 are suitably spaced apart on shaft 123 so that they will coact with roll 122 in forwarding the partly folded envelop without touching the moist gum on the seal flap. Obviously said disks may have their peripheries notched or cut away in part for this purpose.

The disks 121 and roll 122 project the partly folded envelop, with its seal flap gummed, onto an inclined support 127, which is held by transverse rods 128, 128 from the stationary framework. The support 127 provides adjustable stops 129 against which the lower folded edge of the partly formed envelop strikes to arrest the downward movement thereof on said support. These stops are adjustable longitudinally for envelops of different lengths, and are also adjustable vertically for envelops of different heights. For coöperation with the support 127, a swinging plate 130 is provided, which occupies the dotted line position shown in Fig. 3 when the envelop is being projected onto the support. The plate 130 is carried on a rock shaft 131, from which projects a rocking arm 132 that is pivotally connected by a link 133 with a crank 134 on shaft 126. After the envelop is in position in support 127, the plate 130 rocks inwardly to the full line position shown in Fig. 3, whereby its outer free edge 130

will correspond to the line on which the seal flap of the partly formed envelop is to be folded.

The seal flap folding mechanism is somewhat similar to the back or bottom flap folding mechanism above described, in that it consists of a pair of disks 135, Figs. 3 and 9, which are carried on a rocking shaft 136. The latter carries a rocking arm 137, Fig. 1, which is pivotally connected by a link 138 with a crank 139 on shaft 126. Said disks 135 support the journals or trunnions of a roll 140, which corresponds in some respects to the roll 86 of the back flap folding mechanism. However, the roll 140 has no provision for continuous rotation, but is rotated through small arcs intermittently by the engagement of a crank 141 on one of its trunnions with one or the other of a pair of fixed stops 142 and 142', projecting inwardly toward the disk 135 from the fixed framework of the machine. For coöperation with roll 140, a roll 143 is provided, which is the counterpart of roll 94 of the back flap folding mechanism, said roll 143 being journaled in the ends of arms 144 which are pivoted at 145 to the respective disks 135 and yieldingly held by springs 146 to maintain the two rolls in contact.

With the partly folded envelop in position between support 127 and plate 130, the counter-clockwise movement of disks 135 carries the roll 143 against the under side of the extended seal flap, so as to turn up and fold said seal flap over the free edge of plate 130. Just before the end of the throw of the disks in this direction is reached, the crank 141 strikes the stop 142, and thus causes the rotation of the roll 140 through a small arc, whereby the folded edge of the seal flap is moved off the end of plate 130 just far enough to be in the bight of rolls 140 and 143. This movement, however, does not continue for any appreciable distance, but stops almost immediately, since the throw of the disks in a clockwise direction begins at this point. As a consequence, the seal flap is not pressed down against the back of the envelop, but only its folded edge is pinched, and therefore the moist gum on said seal flap has no chance to make contact with any part of the envelop. With its seal flap thus folded, the envelop is completed, and is carried around by the rolls 140 and 143 until the crank 141 strikes the fixed stop 142', to rotate the roll 140 in the opposite direction to which it was previously rotated, thereby discharging the completed envelop from the disks, to allow it to fall into or be received by suitable drying devices, which are not herein shown.

I claim,

1. In an envelop machine, the combination with means for advancing a blank, of means for arresting the advancement of said blank, reciprocating means for folding the side flaps

of the blank, and revoluble means, operable while the blank is at rest, for folding the bottom flap thereof.

2. In an envelop machine, the combination with means for advancing a blank, of means for arresting the advancement of said blank, adjustable reciprocating means for folding the side flaps of said blank, and oscillatory revoluble means for folding the bottom flap of said blank, said folding means operating in immediate succession while the advancement of said blank is arrested.

3. In an envelop machine, the combination with means for advancing a blank, of means for folding a side flap of said blank, comprising a forming plate positioned over said blank, a folder plate for coaction with said forming plate, and means operative to cause said folder plate to successively swing up under said side flap, to move inwardly to turn over and fold said flap, to move outwardly, and to swing down out of the way of the next incoming blank.

4. In an envelop machine, the combination with means for advancing a blank, of means for folding a side flap of said blank, comprising a forming plate positioned over said blank, a folder plate for coaction with said forming plate, and means operative for causing said folder plate to successively swing up under said side flap, to move inwardly to turn over and fold said flap, to release said flap at the end of its inward movement, to move outwardly, and to swing down out of the way of the next incoming blank.

5. In an envelop machine, the combination with means for advancing a blank, of means for folding the side flaps of said blank, oscillatory revoluble rolls for folding the bottom flap of said blank, and oscillatory revoluble rolls for folding the seal flap of said blank.

6. In an envelop machine, the combination with means for advancing a blank, of means for folding the side flaps of said blank, and means for folding the bottom flap of said blank, said bottom flap folding means comprising oscillatory disks, a pair of coacting rolls revolubly mounted on said disks and a forming plate for coaction with said rolls.

7. In an envelop machine, the combination with means for advancing a blank, of means for folding the side flaps of said blank, and means for folding the bottom flap of said blank, said last named means comprising a forming plate, and means for coacting with said forming plate, and operative to fold said bottom flap and remove said blank from beneath said forming plate.

8. In an envelop machine, the combination with means for folding the side flaps of a blank, of means for folding the bottom flap of said blank, and means for folding the seal flap of said blank, said last named means comprising oscillatory disks, a pair of coacting rolls revolubly mounted on said disks,

- a forming plate, and means for rotating said rolls through a small angle to coact with said forming plate for folding said seal flap and for alternately gripping and releasing 5 said blank.
9. In an envelop machine, the combination with means for advancing a blank, of means for folding a side flap of said blank, comprising a forming plate, a folding plate 10 for coaction with said forming plate for folding said side flap, an arm carrying said folding plate, said arm having a substantially square recess therein, a substantially triangular cam operating in said recess for causing said folding plate to successively swing up under said side flap, to move inwardly to turn over and fold said flap, to move outwardly, and to swing down out of the way of the next incoming blank.
- 15 10. In an envelop machine, means for folding a side flap of a blank comprising a forming plate, a folder plate for coaction with said forming plate for folding said flap, an arm carrying said folder plate, said 20 arm having a substantially square recess therein, a substantially triangular cam in said recess operating said arm, and means for folding the bottom flap of said blank, said folding operations taking place in immediate succession while said blank retains a fixed position in the machine.
11. In an envelop machine, a forming plate, and means coacting with said forming plate for folding the bottom flap of a blank and 25 removing said blank from said forming plate, comprising a pair of disks, means for oscillating said disks, a pair of coacting rolls revolvably mounted on said disks, and means for continuously rotating said rolls.
- 30 12. In an envelop machine, means for folding the seal flap of a blank comprising a forming plate, a pair of disks, means for oscillating said disks, a pair of coacting rolls revolvably mounted on said disks, and means 35 for rotating said rolls through a small angle to coact with said forming plate for folding said seal flap and for alternately gripping and releasing said blank.
13. In an envelop machine, means for 40 folding the seal flap of an envelop blank, comprising a forming plate, a pair of disks, a pair of rolls revolvably mounted on said disks, means for oscillating said disks, and means, operable by the oscillation of said 45 disks, for rotating said rolls through small angles to coact with said forming plate for folding said seal flap, and for alternately gripping and releasing the envelop blank.
14. In an envelop machine, the combination with means for advancing a blank, of a forming plate, means for arresting the advancing movement of the blank beneath said forming plate, oscillatory revoluble rolls for folding the bottom flap of said 55 blank over said forming plate, and means for rotating said rolls for withdrawing the folded blank from said forming plate.
15. In an envelop machine, the combination with means for folding the side flaps of a blank, of means for folding the bottom flap 70 of said blank and adjustable means for folding the seal flap of said blank, said last named means comprising oscillatory means, a forming plate for coaction with said oscillatory means, and an adjustable stop arranged to prevent movement of said blank while said seal flap is being folded..
16. In an envelop machine, the combination with a forming plate, of means coacting with said forming plate for folding the 75 side flaps of a blank, means capable of oscillation alternately toward and away from said forming plate for coaction with said plate in folding the bottom flap of said blank, and means for rotating said bottom flap folding means.
17. In an envelop machine, the combination with a side and bottom flap forming plate, of means for coaction with said forming plate for folding the side flaps of a 80 blank, oscillatory means for coaction with said forming plate for folding the bottom flap of said blank, a seal flap forming plate and oscillatory means for coaction with said seal flap forming plate for folding the seal 85 flap of said blank.
18. In an envelop machine, a flap folding mechanism, comprising a forming plate, means for supporting a blank beneath said forming plate, means for advancing a blank 100 by an edgewise movement between said supporting means and said forming plate, means for alining the blank on said supporting means, means for folding the side flaps of the blank, and means for folding 105 the bottom flap of the blank, said folding operations taking place in immediate succession while said blank retains a fixed position on said supporting means.
19. In an envelop machine, means for advancing a blank by an edgewise movement, means for applying adhesive material to the under side of the side flaps of the blank, a forming plate, means for bringing the blank to a state of rest beneath said forming plate 110 and in alinement therewith, means for folding the side flaps over said forming plate to bring their gummed surfaces uppermost, and means for folding the back flap upon said side flaps while the blank remains in a 115 state of rest.
20. In an envelop machine, the combination with means for advancing a blank, of means for arresting the advancement of and alining said blank, reciprocating means for 120 folding the side flaps of said blank, oscillatory revoluble rolls for folding the bottom flap of said blank, and oscillatory revoluble rolls for folding the seal flap of said blank.
21. In an envelop machine, the combina- 125

tion with means for advancing a blank, of means for arresting the advancement of and alining said blank, adjustable means for folding the side flaps of said blank, and 5 means for folding the bottom flap of said blank, comprising a forming plate and unitary means for coaction with said forming plate and operative to fold said bottom flap and remove said folded blank from said 10 forming plate.

22. In an envelop machine, the combination with means for advancing a blank, of means for arresting the advance movement of the blank, means for folding the blank 15 during its period of rest, comprising a forming plate, a folder plate for coaction with said forming plate for folding a side flap of the blank over said forming plate, an arm carrying said folder plate, said arm being 20 pivotally supported at one end and capable of a sliding movement in its support, and means for actuating said arm to successively swing said folder plate upwardly under the side flap, to move inwardly to fold 25 the side flap, to be raised at the end of its inward movement, to move outwardly, and to swing downwardly out of the path of the succeeding incoming blank.

23. In an envelop machine, the combination 30 with means for advancing a blank, of means for arresting the advance movement of the blank, means for folding the blank during its period of rest, comprising a forming plate, a folder plate for coaction with 35 said forming plate for folding a side flap of the blank, an arm carrying said folder plate, said arm being pivotally supported at one end and capable of sliding movement in its support, means for actuating said arm to 40 successively swing said folder plate upwardly under the side flap, to move inwardly to fold the side flap over said forming plate, to be raised at the end of its inward movement, to move outwardly, and to swing 45 downwardly out of the path of the succeeding incoming blank, and means for folding the bottom flap of said blank while the latter remains at rest.

24. In an envelop machine, the combination 50 with means for advancing a blank, of means for arresting the forward movement of the blank, means for folding the side flaps of the blank, and means for folding the back flap of the blank during its period of rest, 55 comprising a pair of coacting rolls, a forming plate having an edge in alinement with the line of fold of the back flap, means for moving said pair of rolls to carry one of said rolls below the forming plate and the 60 other of said rolls above the forming plate, means for retracting said rolls, and means for continuously rotating said rolls to withdraw the folded blank from the forming plate.

65 25. In an envelop machine, the combina-

tion with means for advancing a blank, of means for arresting the forward movement of the blank, means for folding the side flaps of the blank, and means for folding the back flap of the blank while the latter is at rest, 70 comprising a forming plate having an edge corresponding with the line of fold of the back flap, a pair of coacting rolls, with one roll of said pair journaled in fixed bearings and with the other roll of said pair journaled in yielding bearings, means for swinging said pair of rolls in a circular path across the edge of said forming plate, and means for continuously rotating said pair of rolls to withdraw the blank from the 80 folding plate.

26. In an envelop machine, a pair of feed rolls, a supporting plate for the blank, movable belts between said feed rolls and supporting plate for conveying the blank by an 85 edgewise movement, means for gumming the under side of the side flaps during the transit of the blank over said belts, means for arresting the movement of the blank on said supporting plate, a forming plate, 90 means for folding the side flaps over said forming plate, and means for withdrawing the folded blank from the forming plate.

27. In an envelop machine, means for folding the side flaps of the blank, means for folding the back flap of the blank, means for withdrawing the blank from said flap folding mechanism, means for advancing the blank to a gumming mechanism for gumming the seal flap, and means for delivering 100 the folded blank by gravity to mechanism for folding the seal flap, mechanism for folding the seal flap, and means for releasing the folded envelop from the seal flap folding mechanism.

28. In an envelop machine, a seal flap folding mechanism, comprising an inclined plate arranged to receive an envelop blank having its side flaps and back flap folded, means for determining the position of the folded blank upon said inclined plate, a forming plate, means for moving said forming plate upon the folded blank with its edge in alinement with the line of fold of the seal flap, a pair of coacting rolls for folding the seal 115 flap, and means for moving said rolls with their contacting surfaces in a curved path across the folded edge of said forming plate, one roll of said pair of rolls being journaled in fixed bearings and the other roll of said 120 pair being yieldingly held.

29. In an envelop machine, a seal flap folding mechanism, comprising an inclined plate arranged to receive an envelop blank having its side flaps and back flap folded, 125 means for determining the position of the folded blank upon said inclined plate, a forming plate, means for moving said forming plate upon the folded blank with its edge in alinement with the line of fold of 130

the seal flap, a pair of coating rolls for folding the seal flap, means for moving said rolls with their contacting surfaces in a curved path across the folded edge of said forming plate, one roll of said pair being journaled in fixed bearings and the other roll of said pair being yieldingly held, and means for rotating said pair of rolls in one direction at one end of their curvilinear movement to withdraw the folded blank from the forming plate.

30. In an envelop machine, a seal flap folding mechanism, comprising an inclined plate to receive an envelop blank having its side flaps and back flap folded, means for determining the position of the folded blank upon said inclined plate, a forming plate, means for moving said forming plate upon the folded blank with its edge in alignment with the line of fold of the seal flap, a pair of coating rolls for folding the seal flap, means for moving said rolls with their contacting surfaces in a curved path across the folded edge of said forming plate, one roll of said pair of rolls being journaled in fixed bearings and the other roll of said pair being yieldingly held, means for rotating said pair of rolls in one direction at one end of their curvilinear movement to withdraw the folded blank from the forming plate, and means for rotating said pair of rolls in the opposite direction at the opposite end of their curvilinear movement for releasing the folded envelop.

35. 31. In an envelop machine, the combination of the following instrumentalities, operating in the order named, means for advancing a blank by an edgewise movement, means for gumming the under side of the side flaps during said movement, means for arresting the movement of the blank, means for folding the side flaps, means for folding the back flap while the blank is in a state of rest, means for withdrawing the blank from said folding mechanism, means for gumming the seal flap of the blank, means for folding the seal flap, and means for releasing the blank from the seal flap folding mechanism.

50. 32. In an envelop machine, a flap folding mechanism comprising a plate, means for supporting a blank with a flap thereof projecting beyond one edge of said plate, a pair of coöperating rolls normally disposed on the opposite side of said blank from said plate, and means for bodily moving said rolls against said projecting flap to fold the latter over the edge of said plate, whereby the fold is brought into the bight of said rolls.

65. 33. In an envelop machine, a flap folding mechanism comprising a plate, means for supporting a blank with a flap thereof projecting beyond one edge of said plate, rotating means for removing said blank from

said supporting means, normally disposed on the opposite side of said blank from said plate, and means for bodily moving said rotating means into operative blank removing position, whereby said projecting flap is folded over the edge of said plate, prior to the removal of said blank.

34. In an envelop machine, a flap folding mechanism comprising a plate, means for supporting a blank with a flap thereof projecting beyond one edge of said plate, blank engaging means having a path of movement toward said edge of said plate, whereby to fold said projecting flap in the act of engaging said blank, and means for moving said engaging means in the opposite direction to remove said blank from said support.

35. In an envelop machine, a flap folding mechanism comprising a plate, means for supporting a blank with a flap thereof projecting beyond one edge of said plate, a pair of coöperating rolls normally disposed on the opposite side of said blank from said plate, means for bodily moving said rolls to bring the bight thereof adjacent said edge of said plate, whereby the projecting flap of the blank is folded, and the fold is seized in said bight, means for bodily moving said rolls in the opposite direction, to withdraw said blank from said support and means for rotating said rolls.

36. In a folding mechanism, a support for the sheet to be folded, a stationary forming plate above said support, an oscillating roll adapted to coöperate with said forming plate, and means for moving said roll in a circular path from a position below the plane of said forming plate to a position above the edge of the forming plate, whereby a sheet held on said support and projecting beyond the forming plate will be folded over said edge.

37. In a folding mechanism, the combination with a forming plate, of an oscillatory roll for turning over and folding a projecting flap of a blank over said forming plate while said blank is at rest, and means coacting with said folding roll for removing said blank from said forming plate, for applying pressure to the folded blank, and for advancing said blank.

38. In a folding mechanism, the combination with a forming plate, of oscillatory means for folding a blank about said forming plate while said blank is at rest, and revoluble means for coaction with said oscillatory means for removing said blank from said forming plate.

39. In an envelop machine, the combination with a forming plate, of means coacting with said forming plate for folding the side flaps of a blank, a pair of rolls coating with said forming plate for folding the bottom flap of said blank, means for bodily oscillating said rolls to engage said bottom

flap, and means for continuously rotating said rolls to remove said folded blank from beneath said forming plate.

40. In an envelop machine, the combination with means for advancing a blank, of a supporting plate for said blank, a pair of forming plates above said supporting plate, a pair of stops for alining the blank on said supporting plate, means coöperating with 10 said forming plates for folding the side flaps of said blank while on said supporting

plate, and means for simultaneously reciprocating said stops and said forming plates in opposite directions to each other to permit removal of the folded blank from said supporting plate. 15

Dated this 18th day of July 1917.

ABRAHAM NOVICK.
